UNITED STATES PATENT OFFICE.

FRED BUOB, OF CINCINNATI, OHIO.

VEHICLE-BOW TRIMMING.

SPECIFICATION forming part of Letters Patent No. 596,803, dated January 4, 1898.

Application filed July 22, 1897. Serial No. 645,602. (No model.)

To all whom it may concern:

Be it known that I, FRED BUOB, residing at Cincinnati, in the county of Hamilton and State of Ohio, have invented certain new and useful Improvements in Vehicle-Bow Trim-
5 mings, of which the following is a specifica-
tion.

My invention relates to the method of finishing carriage-bows.

10 The object of my invention is to form a valance from the bow of a buggy-top.

By my method I obtain a metal valance finish which can be cheaply and easily applied, being more durable than sheet-metal
15 valances and serving as a thorough protec-
tion instead of injuring the cloth and lining, which is apt to occur with sheet-metal valances.

The features of my invention are more fully
20 set forth in the description of the accompany-
ing drawings, making a part of this specifica-
tion, in which—

Figure 1 is a perspective view of a section
25 of a carriage-top finished with my improved
valance. Fig. 2 is a cross-section on line $x-x$,
Fig. 1. Figs. 3 and 4 are modifications of
Fig. 2. Figs. 5, 6, and 7 are views of another
15 modification showing the use of valances.

A represents, say, the front carriage-bow.
30 The front piece of this carriage-bow is given
the form of a molding by an ordinary friz-
zing-machine. Any desired configuration
may be employed.

35 Figs. 2, 3, 4, and 5 each represent different
configurations of finish.

a represents the covering of the top. b
represents the lining on the inside of the top.
These are attached to the bow A and lap upon
40 each other on the front face of the bow within
the groove or depression on the face of the
bow, as shown in Figs. 2, 3, and 4, and that
at a point to be protected by the valance-bar.

B represents a covering-bar, preferably the
front face being round or oval, as shown.
45 Said bar is bent to the required form and
then secured in position by nails c or clips
secured to the bow. This bar not only pro-
tects the lapped ends of the lining lying with-
in the groove on the face of the bow, but it

forms, with the projections formed upon each 50
side of the groove in the face of the bow, a
neat valance finish.

In Figs. 2 and 3 the configuration of the
face of the covering-bar is oval, while in Fig.
4 it is cylindrical. 55

A material advantage is obtained by hav-
ing the face of the bow shaped to give a val-
ance finish. The depressions or grooves fur-
nish a bed in which the covering-bar rests,
and the shoulders of the grooves furnish an 60
abutting surface for the edges of the cover-
ing-bars, so that the cloth is gripped, as it
were, at the edge of the bar, and the strain
on the cloth is resisted by the edges as well
as by the flat face of the covering-bar, thus 65
preventing the strain on the cloth and lining
from having any tendency to tear at the nail-
holes. The clamping of this covering-bar in
this manner makes not only a superior hold-
ing device, but allows any desired finished 70
appearance to be given to the front bow.

Sheet-metal valances have been employed
to hold the covering and lining in position,
depending upon binding the metal by pinch-
ing down upon the bows. In order to be ef- 75
fective, this pinching has to be so close as to
make a bite of the metal on the cloth and
lining. When strain is applied to the cloth
or lining, they are apt to tear at this biting-
point. My improvement overcomes these ob- 80
jections.

I believe I am the first to form a valance of
the front face of the bow itself, thus avoiding
the necessity of employing a valance-bar
made of a separate piece and attached to the 85
bow and obtaining a stronger, neater, and
cheaper valance.

Having described my invention, what I
claim is—

1. A valance for a carriage-top comprising 90
a bow, a groove formed in the face of the bow,
a carriage-top covering and lining wrapped
around said bow and having their ends over-
lapping within said groove, and a covering-
bar secured to said bow within said groove 95
and upon said overlapping ends, substan-
tially as specified.

2. A bow for a buggy-top, a depression

formed in the face of said bow, a buggy-top covering and lining wrapped around said bow and having their overlapping ends lying within said depression, a covering-bar extended within said depression and over said overlapping ends, said bar being secured to said bow and forming with the exposed portions of said bow, upon each side of the de-

pression, a valance finish, substantially as specified.

In testimony whereof I have hereunto set my hand.

FRED BUOE.
